UNITED STATES PATENT OFFICE

107,519

DESIGN FOR A LAMP

Frank F. Holstein, Chicago, Ill.

Application June 4, 1937, Serial No. 69,671

Term of patent 3½ years

To all whom it may concern:

Be it known that I, Frank F. Holstein, a citizen of the United States, residing at Chicago, Illinois, have invented a new, original, and ornamental Design for a Lamp, of which the following is a specification, reference being had to the accompanying drawing, forming a part thereof.

The dominant feature of my design resides in the parts shown in the solid lines.

I claim:
The ornamental design for a lamp; substantially as shown and described.

FRANK F. HOLSTEIN.
